CLAIM

The ornamental design for a child resistant slide box, as shown and described.

DESCRIPTION

FIG. 1 is a top perspective view embodying the inventive child resistant slide box design showing the box closed; FIG. 2 is a top view of the device as seen in FIG. 1; FIG. 3 is a front view of the device as seen in FIG. 1; FIG. 4 is a right side view of the device as seen in FIG. 1; FIG. 5 is a left side view of the device as seen in FIG. 1; FIG. 6 is a bottom view of the device as seen in FIG. 1; FIG. 7 is a rear view of the device as seen in FIG. 1; and, FIG. 8 is a top perspective view of the device as seen in FIG. 1, wherein the box is open. The broken lines in the figures depict environmental subject matter only and form no part of the claimed design.
